UNDERGARMENT

Samuel L. Berger, Newton Center, Mass., assignor
to Boston Knitting Mills, Inc., Newton, Mass.,
a corporation of Massachusetts

Application April 24, 1934, Serial No. 722,187

5 Claims.

(Cl. 2--78)

The present invention relates broadly to union undergarments and more particularly to the type of union undergarment disclosed in Patent No. 1,916,133.

5 In the union undergarment shown in the patent, an elastic webbing is employed across the top of the seat of the garment, the webbing being attached at the ends thereof to the sides of the garment and reinforcing means being provided for transmitting the strain and pull exerted by the webbing, when extended, to the shoulder of the wearer.

The present invention is directed to a novel method of attaching the ends of the webbing to the garment to bring about a more firm association of these ends with the reinforcing means and generally to obtain a more serviceable union of the end of the web with the garment.

10 The invention will be readily understood by referring to the drawing accompanying the present application; it being understood that the drawing illustrates a preferred embodiment of the present invention and that the invention may be embodied in a variety of forms falling within 15 the scope of the appended claims.

Fig. 1 is a rear view of a garment embodying the invention.

Fig. 2 shows an end portion of an elastic web before the tape is assembled therewith.

20 Fig. 3 shows the end portion of the web with the tape assembled therewith.

Fig. 4 is a sectional view on line 4--4 of Fig. 3.

Fig. 5 is an enlarged sectional view on line 5--5 of Fig. 3.

25 Fig. 6 is a partly broken face view of the end of the web when attached to the garment.

Fig. 7 is an enlarged sectional view on line 6--6 of Fig. 1.

The object of the present invention is to eliminate the necessity of sewing or stitching across the elastic webbing and particularly across or on the part thereof which contains the rubber yarn. It is also important to eliminate the possibility of any of the rubber yarn from being withdrawn from the union or attachment by the repeated pull and strain to which the web is subjected in use. For this double purpose the present invention contemplates the provision of means outside the elastic portion of the web for receiving sewing and stitching for attaching the end of the web to the sides of the garment. As shown in the preferred embodiment of the invention, this additional means takes the form of a short piece of ribbon tape which is interposed between the layers of the folded over end of the web and

is secured therein by any suitable adhesive but preferably by a latex cement such as a vulcanizing latex cement, a non-vulcanizing latex cement, or a vulcanized latex cement.

As shown in the preferred embodiment illustrated in the drawing, a web 10 is employed which consists of a main body portion 11 having the elastic fibre covered squirted rubber yarn and having an inelastic fringe 12 along one edge. The web 10 is attached to the seat 13 of the garment 10 by stitching passing through the fringe 12 and the seat 13. The tape 15 is cemented between the layers of each folded end and has the portion 16 thereof projecting from the top of the web. This projecting portion 16 is attached to the garment by means of stitching 17. The reinforcing tape 18 or the reinforcing flatlock stitching 19, whichever may be employed, is stitched to the portion 16 of the ribbon tape 15, and no stitching of any sort passes through the elastic part 11 of the web. Similarly, the garter loop 20 is attached to the part 16 and to the reinforcing tape 18 (or the flatlock stitching 19) by means of suitable stitching 21 which also passes through the adjacent portion 22 of the garment. The garter loop is also attached intermediate its length to the fringe 12 and the adjacent portion of the seat 13 by means of stitching 24.

It will be understood, however, that if desired a web may be employed having a fringe along both edges, in which case the use of the ribbon tape 15 may be eliminated, for the upper and lower fringes of the web may then be employed to receive all the stitching. The ends of the web will still be folded over and cemented as shown.

The manner of assembling and constructing a garment in the preferred form will now be more particularly described.

As shown in Fig. 2, a layer 25 of a suitable adhesive such as a latex cement is applied to each end portion of the web 10 cut to suitable length. While as shown this cement is applied over the entire width of the web, it will be understood that, if desired, the fringe 12 may be left uncoated. A short piece 15 of inelastic woven ribbon tape or the like is then placed over a part of the adhesive layer and the end of the web is folded over as shown in Fig. 3 so that the tape 15 is disposed between the layers of the folded end with a layer of cement or other adhesive on each face thereof. The tape 15 is preferably so positioned that the lower end thereof registers with the lower edge of the fringe 12 and the upper portion 16 thereof extends upwardly from the folded end of the web 10. These operations are performed at each

end of the web 10. The folded ends are then hammered down or otherwise pressed together, and are permitted to dry for about an hour in the air, thereby forming an intimate and firm 5 union of the tape 15 and the folded layers of the web. If desired the ends may be subjected to a heat treatment, with or without pressure. The adhesive employed should be of such a nature that, while a firm union is obtained, the thus 10 treated ends of the web or rubber yarn should not become hard or brittle.

The web 10 with the ends thus folded and treated is now attached to the top of the seat 13 of the garment by any suitable stitch in a manner well known in the art. The portions 16 at each end of the web are then bartacked to the adjacent portion 22 of the garment by the stitching 17.

The reenforcing tape 18 (or the reenforcing 20 flatlock stitch 19) extending from the bottom of the arm hole to the web and serving to transmit the stretch and pull of the web 10, when distended in use, to the shoulders of the wearer overlap on the portions 16 and are stitched thereto 25 and to the garment by any suitable stitching. Similarly, the garter loops are sewed on as previously described.

It will be seen that by means of the present 30 invention the ends of the elastic web and of the squirmed rubber yarn are firmly cemented; this together with the absence of any stitching across the elastic part of the web serves to minimize the possibility of loosening any of the rubber yarn.

I claim:

35 1. In a union undergarment of the type having a transverse opening in its back portion and dividing the same into a main body portion and a seat; an elastic web attached to and across the top of the seat, said web having a doubled over portion at each end, tape disposed between the layers of said doubled over portion, adhesive disposed in said doubled over portion uniting the layers thereof and the tape, said tape projecting from said doubled over portion and stitching pass-

ing through said projecting portion of the tape and the adjacent portion of the garment for attachment of the ends of the webbing to the garment.

2. In a union undergarment of the type having a transverse opening in its back portion and dividing the same into a main body portion and a seat; an elastic web attached to and across the top of the seat, said web having a doubled over portion at each end, inelastic tape disposed between the layers of said doubled over portion, adhesive disposed in said doubled over portion uniting the layers thereof and the tape, said tape projecting from said doubled over portion and stitching passing through said projecting portion of the tape and the adjacent portion of the garment for attachment of the ends of the webbing to the garment. 5 10 15

3. In a union undergarment having a seat portion; an elastic web attached to and across the top of the seat, said web having a doubled over portion at each end thereof, tape disposed between the layers of the doubled over portion, adhesive uniting said tape and the layers of the doubled over portion, said tape having a part thereof extending from said web, and stitching uniting said part and the garment. 20 25

4. In a union undergarment having a seat portion; an elastic web attached to and across the top of the seat, said web having a doubled over portion at each end thereof, tape disposed between the layers of the doubled over portion, adhesive uniting said tape and the layers of the doubled over portion, said tape having a part thereof extending from said web and reenforcing 30 35 means along the side of the garment attached to the extending part of said tape.

5. In a union undergarment having a seat portion, an elastic web attached to and across the top of the seat, an inelastic tape adhesively united 40 with each end of the web, said tape having a part thereof extending from the web, and stitching uniting said part to the sides of the garment.

SAMUEL L. BERGER.
